DESIGN FOR A FLASHLIGHT

Orville T. Wood, Clinton, Mass., assignor to Blake Manufacturing Corporation, Clinton, Mass., a corporation of Massachusetts

Application September 29, 1936, Serial No. 65,063

Term of patent 7 years

To all whom it may concern:

Be it known that I, Orville T. Wood, a citizen of the United States of America, residing at Clinton, in the county of Worcester and State of Massachusetts, have invented a new, original, and ornamental Design for a Flashlight, of which the following is a specification, reference being had to the accompanying drawing, forming part thereof.

Fig. 1 is a plan view of the flashlight, showing my new design.

Fig. 2 is a side elevational view, and
Fig. 3 is an end view, taken from the rear.

I claim:—

The ornamental design for a flashlight, as shown.

ORVILLE T. WOOD.
